UNITED STATES PATENT OFFICE.

HIRAM C. ROGERS, OF ST. LOUIS, MISSOURI, ASSIGNOR TO SAMUEL G. STAHLHUTH, OF ST. LOUIS, MISSOURI.

BARREL-HEATER.

1,176,246.

Specification of Letters Patent. Patented Mar. 21, 1916.

Application filed February 3, 1915. Serial No. 5,845.

To all whom it may concern:

Be it known that I, HIRAM C. ROGERS, a citizen of the United States, and resident of St. Louis, Missouri, have invented certain new and useful Improvements in Barrel-Heaters, of which the following is a specification.

This invention relates to improvements in barrel heaters, and consists in the novel arrangement, construction and combination of parts as will be fully hereinafter described and claimed.

The object of my invention is to construct a barrel heater, having a drum hingedly yet detachably mounted upon a base so that the drum may be tilted or removed and a means for supporting the drum when in a tilted position so that the interior of the heater may be easily and readily cleansed.

Figure 1, is a front view of my complete invention. Fig. 2, is a fragmental view showing the slotted rib which acts as the hinge for the drum. Fig. 3, is a detail perspective view of a portion of the drum and base showing the arrangement and construction of the hinge.

In the construction of my invention, I provide a base 4, in which is placed an ash-pan 5, the upper portion of the base is provided with a rim 6, and formed upon the rim is a pair of ears 7, through which is passed a pin 8.

On the top of the rim is removably mounted a drum 9, of sufficient size to permit a barrel to be placed over the same and rest upon the rim 6. The said drum is provided with a plurality of ribs 10, which taper at an angle from the surface of the drum downwardly and outwardly to the rim, the said ribs acting as a guide to properly center the barrel around the drum.

One of the ribs 10, is provided with a slot 11, which is designed to fit over the pin

8, carried by the ears 7, and when said rib is properly inserted between the ears, the same acts as a hinge and permits the drum to be tilted in the position shown by dotted lines in Fig. 1. The object of constructing a hinge of this nature, is to permit the drum to be easily and readily removed without removing the pin carried by the ears.

On the top of the drum is placed a cap 12, on which is mounted a flue door 13, and on the cap is formed a lug 14, to which is hingedly carried a supporting rod 15.

The essential feature of my invention is the hinging and tilting of the drum on the base, so that access may be had to the fire box in the base and the interior of the drum.

Heretofore barrel heaters have been constructed in a manner that in order to gain access to the interior, it is necessary to remove bolts and lift the entire drum off of the base.

A barrel heater of my construction can be tilted in the position as shown by dotted lines in Fig. 1, no matter how hot the drum might be.

Having fully described my invention what I claim is:

A barrel heater comprising a base, a rim forming the top of said base, a drum having a plurality of tapered ribs, one of said ribs provided with a slot, a pair of ears formed on the rim between which the slotted rib is inserted, a supporting rib hingedly attached to the top of the drum for supporting said drum when in a tilted position, substantially as specified.

In testimony whereof, I have signed my name to this specification, in presence of two subscribing witnesses.

HIRAM C. ROGERS.
